UNITED STATES PATENT OFFICE.

DAVID MACDONALD, OF LONDON, ENGLAND.

LEAF-TURNER.

No. 917,782.

Specification of Letters Patent. Patented April 13, 1909.

Application filed February 10, 1908. Serial No. 415,064.

To all whom it may concern:

Be it known that I, DAVID MACDONALD, a subject of the King of Great Britain, residing at London, in England, have invented certain new and useful Improvements in Leaf-Turners; and I do hereby declare the following to be a full, clear, and exact description of the invention, such as will enable others skilled in the art to which it appertains to make and use the same.

This invention relates to improvements in the construction of apparatus for turning over the leaves of a book, more especially of a music book held on a piano rack, and of the type in which centrally operated turning arms having clips to grip the sheets are released intermittently from a catch holding them at one side of the rack.

The object of the invention is to simplify the construction of the leaf clips and the release gear and to render the latter adjustable, so as to remedy certain defects which have been found to make such an apparatus difficult of operation in practice.

The accompanying drawings illustrate the invention.

Figure 1, is a front elevation of the leaf turner. Fig. 2, is a plan of Fig. 1. Fig. 3, is an enlarged view of the release gear. Fig. 4, is a plan of Fig. 3. Fig. 5, is an end view of Fig. 3, and Fig. 6, is a side elevation showing the operation of the sheet clips.

A series of arms A B C D are pivoted on a central spindle E, each arm is provided at its outer end with a spring clip F G H I in which the sheets to be turned are placed before using. Each arm is connected by means of cords such as J, K, with springs such as L, M, fixed to the back board N; the book rest O is provided with pegs P and Q and an elastic cord R is attached to the upright S the book being inserted within the cord R and the covers kept in place by the pegs P and Q. The levers A B C D having the leaves inserted in the spring clips F G H I are turned about the pivot E and brought into operative position by pressing them past the projecting edge of the cam T of the release gear, carried by the flexible bracket W.

So far the parts described are old.

The improvements consist firstly in forming the sheet clips as shown in Fig. 6; each clip is attached to the turning arms A, B, C, D respectively at the same level the arms being bent as shown in Fig. 1, to bring them into this position; one half of each clip has

preferably, though not necessarily, a distance piece such as f g i h attached to it, and the two plates such as m and G of a clip are connected to each other by a pivoted joint d, the top ends being pressed together by springs e; the clips are so arranged that they may be all pressed together at once as shown in Fig. 6 so as to open the sheet ends and while in their compressed position they are held temporarily by a hinged clip p so that the sheets may readily be inserted. The pivot E is formed by a pin extending across a bracket q with turned up sides which sides form a bearing for the pivot pin; the bracket is attached to the music stand by screws r, r.

The release gear consists of the compound cam T, b, firmly attached to the spindle U the faces a, and b being cut away as shown in Figs. 3 and 4 so as to retain or release respectively the plates such as k attached to the sheet clip. The cam is operated by the lever X operating against the action of a coil spring u surrounding the spindle U and secured at one end to the cam b and at the other end to the loose disk v. The amount of rotary movement that can be imparted to the cam b is limited by cutting out a segment w in which operates the stop x. The position of this cut out segment is of considerable importance, one side thereof being formed in such a position as to limit the stroke of the operating lever, by hitting the stop x on the bracket W when the lever is depressed. In machines with an unlimited stroke it has often been the case that two leaves would be turned at one time which is prevented in this machine by the means stated. The amount of tension on the spring u is adjusted by twisting the disk v, the said disk being secured in place by the screw y threaded in one arm of the rigid bracket Y, while passing freely through a hole in the flexible bracket V.

The release cam T, b, is attached to its supporting spindle by a screw, or other suitable connection which can be slackened; by this means a further advantage is attained that the position of the operating lever X can readily be altered to any position desired.

It must be understood that though referred to herein as operated by springs, both the oscillation of the turning arms and the release gear may be actuated by elastic rubber devices if desired. In the other arm of the rigid bracket Y a screw z is threaded so that it can rotate freely at the flexible bracket

- end to which it is connected by a washer on the inside of the flexible bracket so that when rotated the screw draws the flexible bracket W' to or from the rigid bracket; as the spin- 5 die U is supported in the lugs V V of the flexible bracket, the cam T, b, is also drawn to or from the plate k by which it operates the turning arms and thus the amount of overlap is adjusted.
- 10 Pressure on the cup Z of the lever X whether by a puff of breath from the player, or by a touch of the finger, will turn the spindle U and consequently the cam T and will thereby remove the projecting portions 15 of the cam away from the path of one of the arms such as B, which will thereupon turn over to the left carrying its leaf with it. By another puff, or touch, each of the other arms is also caused to turn over taking the sheet 20 with it, until all the sheets are turned. Though shown with four arms it is clear that any larger number of arms desired may be arranged for. It will be seen that when one of the projecting edges of the cam T is 25 removed from one arm the other projecting edge b will temporarily catch the succeeding arm and hold it until a is again in place for so doing.

What I claim as my invention, and desire 30 to secure by Letters Patent, is:—

1. In a leaf turner, and in combination, a framework to carry a book, spring operated pivoted arms carrying sheet clips, a release cam mounted on a spindle, a coil spring at- 35 tached at one end to the cam and at the other end to a stationary part, a flexible bracket carrying the cam spindle, a rigid bracket ad- joining the flexible bracket, and a screw in same connecting it with the flexible bracket, 40 substantially as and for the purpose set forth.

2. In a leaf turner, and in combination, a framework to carry a book, spring operated pivoted arms carrying sheet clips, a release cam mounted on a spindle having a segment 45 cut out, a stop piece on the flexible bracket operating in the said segment, a coil spring attached at one end to the cam and at the other end to a stationary part, a flexible bracket carrying the cam spindle, a rigid bracket ad- 50 joining the flexible bracket, and a screw in same connecting it with the flexible bracket, substantially as described herein.

3. In a leaf turner, and in combination, a framework to carry a book, spring operated pivoted arms carrying sheet clips, a release cam mounted on a spindle, a coil spring at- 55 tached at one end to the cam and at the other end to a stationary part, a flexible bracket carrying the cam spindle, a rigid bracket ad- 60 joining the flexible bracket, a screw in same connecting it with the flexible bracket in order to adjust the latter, a loose collar on the cam spindle carrying the stationary end of the coil spring and provided with holes in its 65 periphery, and a screw carried by the rigid

bracket for adjusting same, substantially as described herein.

4. In a leaf turner, and in combination, a framework to carry a book, spring operated pivoted arms carrying sheet clips, a release cam mounted on a spindle having a segment 70 cut out, a stop piece on the flexible bracket operating in the said segment, a coil spring attached at one end to the cam and at the other end to a stationary part, a flexible bracket carrying the cam spindle, a rigid bracket ad- 75 joining the flexible bracket, a screw in same connecting it with the flexible bracket, a loose collar on the cam spindle carrying the sta- 80 tionary end of the coil spring and provided with holes in its periphery, and a screw carried by the rigid bracket for adjusting same, substantially as described herein.

5. In a leaf turner, and in combination, a framework to carry a book, spring operated pivoted arms carrying sheet clips, an inde- 85 pendent bearing bracket for the spring oper- ated pivoted arms, a release cam mounted on a spindle having a segment cut out, a stop 90 piece on the flexible bracket operating in the said segment, a coil spring attached at one end to the cam and at the other end to a sta- 95 tionary part, a flexible bracket carrying the cam spindle a rigid bracket adjoining the flexible bracket, a screw in same connecting it with the flexible bracket, a loose collar on the cam spindle carrying the stationary end of the coil spring and provided with holes in its periphery, and a screw carried by the rigid 100 bracket for adjusting same, substantially as and for the purpose set forth.

6. In a leaf turner, and in combination, a framework to carry a book, spring operated turning arms having sheet clips with extend- 105 ed bottom portions, distance pieces therebe- 110 tween, springs between the two arms of the clip, a catch for securing all the clips together with their sheet ends open, a release cam mounted on a spindle, a coil spring attached at one end to the cam and at the other end to a stationary part, a flexible bracket carrying the cam spindle, a rigid bracket adjoining the flexible bracket, and a screw in same con- 115 necting it with the flexible bracket, substan- tially as described herein.

7. In a leaf turner, and in combination, a framework to carry a book, spring operated turning arms having sheet clips with extend- 120 ed bottom portions, distance pieces there be- 125 tween, springs between the two arms of the clip, a catch for securing all the clips together with their sheet ends open, a release cam mounted on a spindle having a segment cut out, a stop piece on the flexible bracket oper- ating in the said segment, a coil spring at- 130 tached at one end to the cam and at the other end to a stationary part, a flexible bracket carrying the cam spindle, a rigid bracket ad- joining the flexible bracket, and a screw in

same connecting it with the flexible bracket, substantially as described herein.

8. In a leaf turner, and in combination, a framework to carry a book, spring operated turning arms having sheet clips with extended bottom portions, distance pieces there-between, springs between the two arms of the clip, a catch for securing all the clips together with their sheet ends open, a release cam mounted on a spindle having a segment cut out, a stop piece on the flexible bracket operating in the said segment, a coil spring attached at one end to the cam and at the other end to a stationary part, a flexible bracket carrying the cam spindle, a rigid bracket adjoining the flexible bracket, a screw in same connecting it with the flexible bracket in order to adjust the latter, a loose collar on the cam spindle carrying the stationary end of the coil spring and provided with holes in its periphery, and a screw carried by the rigid bracket for adjusting same, substantially as described herein.

9. In a leaf turner, and in combination, a framework to carry a book, spring operated turning arms having sheet clips with extend-

ed bottom portions, distance pieces there-between, springs between the two arms of the clip, a catch for securing all the clips together with their sheet ends open, an independent bearing bracket for the spring operated pivoted arms, a release cam mounted on a spindle having a segment cut out, a stop piece on the flexible bracket operating in the said segment, a coil spring attached at 30 one end to the cam and at the other end to a stationary part, a flexible bracket carrying the cam spindle, a rigid bracket adjoining the flexible bracket, a screw in same connecting it with the flexible bracket in order to adjust 35 the latter, a loose collar on the cam spindle carrying the stationary end of the coil spring and provided with holes in its periphery, and a screw carried by the rigid bracket for adjusting same, substantially as described 40 45 herein.

In testimony whereof, I have affixed my signature, in presence of two witnesses.

DAVID MACDONALD.
